[57] CLAIM

The ornamental design for punch-blade holder, as shown and described.

DESCRIPTION

FIG. 1 is a perspective view of a punch-blade holder showing my design;

FIG. 2 is an elevational front view of the punch-blade holder of FIG. 1;

FIG. 3 is a right-side view of the punch-blade holder of FIG. 1;

FIG. 4 is a top plan view of the punch-blade holder of FIG. 1;

FIG. 5 is a left-side view of the punch-blade holder of FIG. 1;

FIG. 6 is a bottom view of the punch-blade holder of FIG. 1;

FIG. 7 is a cross-sectional view taken along 7—7 line in FIG. 4; and,

FIG. 8 is a reference view showing a state that the punch-blade holder is used in a punch.

Rear view appears symmetrically with the elevational front view of FIG. 2.

The broken line showing of a punch is for illustrative purposes only and forms no part of the claimed design.
